SECURITY CAMERA

George Hardy, Huntington, N.Y., assignor to Bell Security Systems, Inc., New York, N.Y.

Filed Feb. 24, 1970, Ser. No. 21,594

Term of patent 14 years

Int. Cl. D16—01

U.S. Cl. D61—1

FIG. 1

FIG. 2

FIG. 3

FIG. 4

FIG. 5

FIG. 1 is a left front perspective view of a security camera according to my new design;

FIG. 2 is a top plan view thereof;

FIG. 3 is a left side elevational view thereof, the right side being identical;

FIG. 4 is a rear elevational view thereof; and,

FIG. 5 is a bottom plan view thereof.

I claim:

The ornamental design for a security camera, as shown and described.
